DESIGN FOR A BICYCLE FRAME

John R. Alexander, Paris, Tex.

Application July 27, 1940, Serial No. 93,958

Term of patent 14 years

To all whom it may concern:

Be it known that I, John R. Alexander, a citizen of the United States and a resident of Paris, in the county of Lamar and State of Texas, have invented the new, original, and ornamental Design for Bicycle Frames, of which the following is a specification.

Reference is had to the accompanying drawing, forming part thereof, in which:

Figure 1 is a perspective view of a bicycle frame, showing my new design.

Figure 2 is a plan view thereof.

Figure 3 is a front elevation of the bicycle frame.

I claim:

The ornamental design for a bicycle frame, as shown.

J. R. ALEXANDER.
